(57) **CLAIM**

The ornamental design for a ceiling fan blade, as shown and described.

DESCRIPTION

FIG. 1 is a perspective view of a ceiling fan blade in accordance with my new design, shown in the environment of a ceiling fan;

FIG. 2 is a top plan view of the ceiling fan blade shown in FIG. 1, but shown in a detached position and without the ceiling fan environment;

FIG. 3 is a bottom plan view thereof;

FIG. 4 is a left-side elevation view thereof;

FIG. 5 is a right-side elevation view thereof;

FIG. 6 is a front elevation view thereof; and,

FIG. 7 is a rear elevation view thereof.

The broken lines shown in FIG. 1 illustrate environmental structure and portions of the ceiling fan blade. The broken lines in the remaining views illustrate portions of the ceiling fan blade. None of the broken lines form part of the claimed design.

The lighter and closely spaced lines in the drawings are surface shading and are not surface ornamentation.
